No. 37,272.

Patented December 20, 1904.

UNITED STATES PATENT OFFICE.

WILLIAM C. HUSS, OF CINCINNATI, OHIO.

DESIGN FOR A BAR-FIXTURE.

SPECIFICATION forming part of Design No. 37,272, dated December 20, 1904.

Application filed November 25, 1904. Serial No. 234,300. Term of patent 7 years.

To all whom it may concern:

Be it known that I, WILLIAM C. HUSS, a citizen of the United States of America, and a resident of Cincinnati, county of Hamilton, State of Ohio, have invented a certain new, original, and ornamental Design for a Bar-Fixture, of which the following is a specification.

Figure 1 is a front elevation of a bar-fixture embodying my new design. Fig. 2 is an end

elevation of the same. Fig. 3 is a top plan view of the same.

What I claim is—

The ornamental design for a bar-fixture substantially as shown.

WILLIAM C. HUSS.
